UNITED STATES PATENT OFFICE.

JOHN HEBERLING, OF ROCHESTER, NEW YORK, ASSIGNOR TO HICKOK MANUFACTURING COMPANY, INC., OF ROCHESTER, NEW YORK, A CORPORATION OF NEW YORK.

BELT-BUCKLE.

1,363,318.

Specification of Letters Patent. Patented Dec. 28, 1920.

Application filed February 24, 1920. Serial No. 361,068.

To all whom it may concern:

Be it known that I, JOHN HEBERLING, a citizen of the United States, and resident of Rochester, in the county of Monroe and State 5 of New York, have invented certain new and useful Improvements in Belt-Buckles, of which the following is a specification.

The present invention relates to belt buckles and an object thereof is to provide 10 a simple, effective and inexpensive means for clamping the free end of the belt to the buckle. Another object of the invention is to improve that type of belt buckle in which the frame is formed from a single piece of 15 sheet material with slotted side flanges on which a clamping slide operates by constructing the clamping slide so that it will not wear the walls of the slots and render the clamping slide ineffective. Another object of the invention is to provide a simple 20 and effective means for securing the inner end of the strap or belt to the buckle so that the inner end will lie firmly against the free end and at the same time bind such free 25 end against the buckle frame.

To these and other ends, the invention consists of certain parts and combinations of parts, all of which will be hereinafter described, the novel features being pointed out 30 in the appended claims.

In the drawings:

Figure 1 is a fragmentary view of a belt employing the present invention;

Fig. 2 is a fragmentary edge view of the 35 belt with the buckle thereon;

Fig. 3 is a longitudinal enlarged section through the belt buckle;

Fig. 4 is a transverse section through the belt buckle showing the manner of securing 40 the inner end of the strap;

Fig. 5 is a rear view of the belt buckle with the strap disconnected therefrom;

Fig. 6 is a fragmentary longitudinal section showing the manner in which the strap 45 end is clamped;

Fig. 7 is a transverse section through the belt buckle in the plane of the slide;

Fig. 8 is a detail view of another embodiment of the slide;

50 Figs. 9 and 10 are fragmentary sectional views of the form of slide shown in Fig. 8, the member on the slide being illustrated in two positions;

Fig. 11 is a fragmentary sectional view of another embodiment showing the different 55 form of slide in clamping position;

Fig. 12 is a transverse section of a belt buckle employing the slide illustrated in Fig. 11; and

Fig. 13 is another detail fragmentary view 60 of the slide shown in Figs. 11 and 12.

Referring first to the embodiment shown in Figs. 1 to 7, there is employed a buckle frame, in this instance, in the form of a front plate 1 on which a monogram or other 65 ornamentation may be placed having rearwardly extended side flanges 2. The strap or belt 3 has one end secured to this buckle frame and this securing means which forms one of the features of this invention, is preferably in the form of a bar 4 mounted to slide on the buckle frame preferably at a slight angle to the rear face of the front plate 1 of the buckle frame. This result in this instance is secured by providing the 70 side flanges 2 with slots 5, said slots being at oblique angles to the front plate of the buckle frame and having the ends of the bar 4 working therein. The inner end of the strap 3 is passed about this bar 4 and is 80 secured by a head and socket fastener 6. In order that the headed device of the fastener may be passed under the bar 4, the bar is deflected at 7. It is apparent that the pull 85 or tension on the bar 4 will tend to move said bar toward the outer or lower ends of the slots 5 and in this way cause the secured or inner end of the belt or strap to be brought into a frictional engagement with the free end 3^a of the belt or strap lying between the bar and the rear face of the front plate 1.

A clamping means of novel construction is provided for securing the free end 3^a of the belt or strap. This clamping means in 95 all illustrated embodiments is in the form of a slide 8 guided on ways 9 on the buckle frame. It is preferred to form these ways in the side flanges 2 of the buckle frame by providing slots in said flanges, these slots 100 preferably having their inner ends extending substantially parallel with the front plate 1 while their outer ends incline slightly with reference to said front plate so that the slide may lie at their inner ends to permit the free 105 movement of the strap beneath the slide. A

feature of this slide is its wide or extended bearing on the guide 9, so that the thin metal of which the side flanges are made will not be worn adjacent the clamping position of 5 the slide to prevent the latter entering into binding engagement with the strap. It is also preferred to mount on the slide 8 a movable member 10 for engagement with the free end 3^a of the strap. The slide in the 10 embodiments shown in Figs. 1 to 10 is formed from a single piece of sheet metal bent along opposite edges at 8^a to provide a wide bearing surface and confining means for the movable member 10. The latter, in the embodiment shown in Figs. 1 to 7 is in the form of a roller which has its ends projected through the slots 9 and also confined by laterally turned portions 8^b at the ends of the slide, these laterally turned portions being also turned inwardly to cooperate with the outer faces of the flanges 2 in order to 15 confine the slide against longitudinal movement in the slots 9. The flanges 8^a extend into the slots and prevent the loose lateral 20 movement of the slide in the slots.

The operation of the embodiment of the invention shown in Figs. 1 to 7 is effected by moving the slide to the dotted line position shown in Fig. 3 when the strap end 3^a may 25 be introduced between the slide and the rear face of the front plate 1. The ends of the slide which project beyond the side flanges 2 are then engaged with the fingers and the slide is moved toward the outer end of the 30 slot so as to bring the movable member 10 in engagement with the belt. Tension then placed upon the strap 3^a will cause the roller 10 to move on the slide 8 toward the outer 35 end of the slot and produce a binding action 40 on said strap.

In the embodiment shown in Figs. 8, 9 and 10, the parts are the same as those shown in Figs. 1 to 7 except that, instead of a roller 10, a plate 10^a is provided with a laterally 45 and inwardly turned flange 11 which is adapted to engage with the strap end 3^a. The operation is the same as the other embodiment except that the movable member 10^a slides laterally on the slide 8 and at the 50 same time has a partial rocking movement.

In the embodiment of the invention shown in Figs. 11 to 13 inclusive, the guide slots 9^a are reduced in width and the slide 8^a is in the form of a plate having its edges operating in said slots 9^a and held therein by washers 12 secured to the ends of the plate. The plate 8^a has a portion 8^d bent from one piece of metal therewith and extended over it, this portion 8^d being slotted at 8^e in order 55 to receive the movable member 10^b. This movable member is in the form of a rocking plate having lugs or projections 10^c at its inner edge extending through slots in the portion 8^d and bent over in order to hold 60 said member to the movable slide. The op-

eration of this embodiment is the same as in the other two except that the movable member on the slide is pivoted instead of being bodily movable.

A belt buckle constructed in accordance 70 with this invention secures the end of the belt in such a manner that the secured end moves into firm binding engagement with the free end of the belt. A slide is provided which has extended bearing on two 75 slotted flanges so that the wearing of the flanges is prevented. This slide has also a movable member which is brought into clamping engagement with the free end of the belt after the slide has been moved by 80 hand toward the outer end of the slot. At the inner end of the slot, the movable member lies out of contact with the free end of the belt so that such free end may be readily fitted to or disconnected from the belt buckle. 85

What I claim as my invention and desire to secure by Letters Patent is:

1. A buckle comprising a frame formed with a front plate and rearwardly extending side flanges provided with slots inclined 90 with reference to the rear face of the front plate, and a clamping slide movable in said slot and having extended transverse bearing on the walls of the slots to prevent the 95 wearing of said walls.

2. A belt buckle comprising a frame having a surface against which the free end of a belt is clamped, a clamping member movable on said frame toward and from the surface, and a device mounted on said 100 clamping member and carried into engagement with the free end of a belt lying against the clamping surface of the frame, said device having a further movement on the member toward the clamping surface 105 of the frame under the action of tension on the belt in the direction of the length of the latter.

3. A belt buckle comprising a frame having a surface against which the belt end is 110 clamped, a slide movable on said frame toward and from said surface, and a device mounted on the slide and carried thereby into engagement with a belt lying against the clamping surface of the frame, said device having a further movement on the member toward the clamping surface of the frame under the action of tension on the belt in the direction of the length of the latter. 115

4. A belt buckle comprising a frame formed with a front plate, the rear face of which provides a surface against which a belt end is clamped, said frame also having lateral side flanges provided with slots inclined with reference to the front plate, a clamping slide movable in the slots toward and from the clamping surface, and a device mounted on said slide and carried thereby into engagement with the belt lying against 125 130

the clamping surface of the frame, said device having a further movement on the member toward the clamping surface of the frame under the action of tension on the belt.

5. A belt buckle comprising a frame and a clamping slide movable on said frame and provided with a bearing surface and limiting means on opposite sides of the bearing 10 surface, said clamping slide having a portion movable on the bearing surface between said limiting means to coöperate with the free end of the belt.

6. A belt buckle comprising a frame 15 formed with a front plate, and a pair of laterally extending side flanges provided with slots arranged at slight angles to the front plate, and a clamping slide movable in said slots and provided with a bearing 20 surface, and limiting means on opposite sides of the bearing surface, said slide also being provided with a movable portion operating on the bearing surface between the limiting means to engage with the free end 25 of the belt.

7. A belt buckle comprising a frame formed with a front plate and laterally extending side flanges having slots at angles to the plane of the front plate, and a clamping 30 slide movable in said slots and formed from a single piece of material with its ends bent to coöperate with the outer sides of the flanges to limit the longitudinal movement of said slide, said slide also having a movable 35 portion for engaging with the free end of the belt.

8. A belt buckle comprising a frame formed with a front plate and laterally extending side flanges provided with slots inclined to the plane of the front plate, and a clamping slide movable in said slots and formed from a single piece of material having portions at its ends coöoperating with the outer faces of the side flanges and having 40 limiting means along opposite sides, said slide having a movable portion between 45

said limiting means for engaging with the free end of the belt.

9. A belt buckle comprising a frame having a surface against which the free end 50 of a belt is clamped, a member movable on said frame toward and from the surface, and a roller mounted on said member and carried thereby into engagement with a belt lying against the clamping surface of the 55 frame, said roller having a further movement on the clamping member toward said clamping surface of the frame under the action of tension on the belt in the direction of the length of the latter.

10. A belt buckle comprising a frame having a surface against which the belt is clamped, a slide movable on said frame toward and from said surface, and having a bearing surface which lies at any slight 65 angle to the clamping surface of the frame when said slide is adjusted toward such clamping surface, and a device mounted on the slide and carried thereby into engagement with a belt lying against the clamping 70 surface of the frame, said device having a further movement on the bearing surface toward the clamping surface of the frame under the action of tension on the belt in the direction of the length of the latter.

11. In combination with a belt, a buckle comprising a frame formed with a front plate having a surface against which the free end of the belt is clamped, said frame also having laterally extending side flanges 80 provided with slots inclined to the clamping surface of the frame, a bar movable in said slots and having the inner end of a belt secured thereto and adapted to be brought by said bar into frictional engagement with 85 the free end of the belt resting against the clamping surface of the frame, and clamping means carried by the side flanges of the frame to hold adjustable the free or outer end of the belt against the clamping face 90 of the frame in connection with said bar.

JOHN HEBERLING.
